UNITED STATES PATENT OFFICE.

JAMES RAMSEY SPEER, OF PITTSBURG, AND GEORGE H. HARVEY, OF GLENFIELD, PENNSYLVANIA, ASSIGNORS TO BROWNSVILLE GLASS COMPANY, OF PITTSBURG, PENNSYLVANIA, A CORPORATION OF PENNSYLVANIA.

GLASS-DRAWING APPARATUS.

No. 824,750.

Specification of Letters Patent.

Patented July 3, 1906.

Application filed November 16, 1905. Serial No. 287,599.

To all whom it may concern:

Be it known that we, JAMES RAMSEY SPEER, residing at Pittsburg, and GEORGE H. HARVEY, residing at Glenfield, in the county of Allegheny and State of Pennsylvania, citizens of the United States, have invented or discovered new and useful Improvements in Glass-Drawing Apparatus, of which the following is a specification.

Our invention relates to apparatus for making glass, and has particular reference to the manufacture of hollow cylinders, though it is not restricted to the same. It has also special reference to apparatus for moving the drawn glass from a vertical to a horizontal position. By our invention the drawn-glass cylinders are preferably suspended from their upper ends and swung after having been cracked off from the glass in the drawing pot or tank into a horizontal position, portions between the top and bottom of the cylinder being preferably supported by arms. It will be observed that we cause the top of the cylinders to be swung down instead of the bottom to be swung out, as is the usual practice, and that the cylinders are at once swung away from over the pot or furnace, so that the drawing of another cylinder may be preceded with even before the last cylinder has been entirely lowered.

Our invention also relates to an improved punt or drawing-tool, so constructed that it may be separated into sections.

Referring to the drawings, which form a part of this specification, Figure 1 is an elevation, partly in section, showing one form of our invention; Fig. 2, a section on the line 11-11 of Fig. 1; Fig. 3, a plan view of the clamping device for securing the drawing ring or iron to the draft mechanism, and Fig. 4 an elevation of a second form of our invention.

On the drawings, 1 represents diagrammatically any means for containing the molten glass and maintaining it in a condition for drawing. It may be a furnace or reheating device of any desired kind, the same not constituting in its specific construction any part of the present invention.

2 represents a glass cylinder drawn from the furnace 1 and attached at its upper end to the lower edge of the drawing ring or iron 3, which is temporarily secured beneath the

cap or plate 4 by means of the two semicircular arms 5, pivoted together on the pin 6, held in place by the hinge-strap 7, secured to the top of the cap 4. The ring 3 is provided externally with the annular groove 8 to receive the annular ribs 9 on the arms 5. 9 represents a slip-ring for securing the arms 5 around the cap 4.

Screwed into the top of the cap 4 is the pipe 10, provided with the ring or lug 11, by which the drawing-tool and glass cylinder may be supported. The lug 11 sits on the fork 12, the pipe 10 being between the members of the fork. The fork 12 is carried by the arm or jib 13, which may be raised and lowered by any mechanism suitable for the purpose. It is no part of the present invention to provide any means to raise or lower the drawing-tool.

Swinging on a pin 14 near the floor is a bed or carriage capable of being swung from a horizontal to a vertical position by the cord 15 passing over the pulley 16; but other means for raising the carriage will readily suggest themselves to those conversant with the art. The fixed bar 17 forms a rest for the bed to hold it in its vertical position.

The bed is preferably composed of the bar 18, having at least its upper end hollow to provide a passage-way for the ear 19, having the wheels 20, guided in the grooves 21 in the bar. The car is provided with a pair of arms 22, which extend one on each side of the cylinder and have each a notch 23 near its outer end to engage the pins 24 on the ring or iron 3.

The car 19 is provided with the pinion 25, which rolls along the fixed rack 26 on the bar 18. Rotatable with the pinion is a ratchet-wheel 27, with which engages the pawl 28 to hold the car in any position to which it may be elevated. The car is preferably raised and lowered by means of the cord 29, passing over the pulley 30 on the bar 18; but any other suitable means may be provided whether hand or power operated.

31 represents supports on the bar 18 to support the cylinder as it is being swung down on the pin 14. These supports are shown fixed on the bar; but our invention is not limited to this construction.

We do not limit ourselves to any specific travel of the car 19, as it may travel the

whole length of the bar, if desired, and be kept with its arms 22 in contact with the pins 24 during the whole travel of the drawing-tool.

After the cylinder 2 has been drawn its bottom is cracked off in the usual manner, the carriage is brought up to its vertical position, as shown, and the arms 22 raised, so as to engage the pins 24. The arms 5 are then opened and the cap 4 and its connected parts raised or removed to permit the swinging down of the top of the cylinder. The bar 18 is lowered in any approved manner, as by the cord 15, the bar having been started downward in any desired manner until the center of gravity of the carriage and its load passes the vertical plane which includes the pivot 14. The manner of causing the carriage to descend is not material, as it can be accomplished many ways. For example, as shown in Fig. 4, a pinion 32 on the pin 14 is caused to move by the pinion 33 by the application of any convenient power to the shaft 34, on which the pinion 33 is secured.

After the cylinder 2 has been moved from over the furnace a freshly-heated ring 3 is secured to the cap 4 and another cylinder is drawn and removed as before.

The manner of using the invention may be varied. For example, the carriage may be raised to vertical position with the arms 22 below the pins 24 and then the cylinder lowered, so that the pins shall rest on the arms.

This would also be the procedure where the arms 22^a are fixed on the bar 18, as shown on Fig. 4.

The movability of the arms 22 has a further purpose—namely, to enable the support to be adjustable to various lengths of cylinders.

Having described our invention, we claim—

1. In the manufacture of vertical drawn glass, means to support and swing the glass downwardly on a center relatively distant from the top of the glass.

2. In the manufacture of vertical drawn glass, a support for the glass, and means for swinging the top of said support downwardly.

3. In the manufacture of vertical drawn glass, a support for the glass having thereon an adjustable member to support drawn articles of various lengths.

4. In the manufacture of glass, a drawing-tool consisting of a drawing-ring and a cap therefor detachable therefrom, and means to support and swing the glass with the ring thereon downwardly on a center relatively distant from the top of the glass.

Signed at Pittsburg, Pennsylvania, this 13th day of November, 1905.

JAMES RAMSEY SPEER.
GEORGE H. HARVEY.
